COVER FOR SADDLES OF SPINNING FRAMES

Robert Rulon-Miller and Warner H. Tabor, Bristol, R.I., assignors to Dixon Corporation, a corporation of Rhode Island

Filed July 10, 1959, Ser. No. 56,733

Term of patent 14 years

(Cl. D92—15)

FIG. 1 is a side elevational view of a cover for saddles of spinning frames showing our new design;

FIG. 2 is a top plan view thereof;

FIG. 3 is a sectional view on line 3—3 of FIG. 1; and
FIG. 4 is a perspective view thereof.

The broken line showing of portions of a spinning frame is for illustrative purpose only.

We claim:

The ornamental design for a cover for saddles of spinning frames, as shown and described.
